WORK SUPPORT

Filed Feb. 12, 1920

Patented May 22, 1923.

1,456,040

UNITED STATES PATENT OFFICE.

WILLIAM THOMAS BUCKINGHAM ROBERTS, OF LEICESTER, ENGLAND, ASSIGNOR TO UNITED SHOE MACHINERY CORPORATION, OF PATERSON, NEW JERSEY, A CORPORATION OF NEW JERSEY.

WORK SUPPORT.

Application filed February 12, 1920. Serial No. 358,023.

To all whom it may concern:

Be it known that I, WILLIAM THOMAS BUCKINGHAM ROBERTS, a subject of the King of England, residing at Leicester, Leicester-
shire, England, have invented certain Im-
provements in Work Supports, of which the
following description, in connection with the
accompanying drawings, is a specification,
like reference characters on the drawings
10 indicating like parts in the several figures.

This invention relates to work supports
for machines used in bottoming shoes, such
as nailing machines or other metallic fasten-
ing inserting machines or sewing machines,
15 and pertains particularly to that type of
work support comprising an element for di-
rectly engaging and supporting the work and
over which the work is moved during suc-
cessive operations of the machine. For con-
20 venience of description, the work engaging
and supporting element will be hereinafter
sometimes referred to in the specification
and claims as a horn. As so used, the term
"horn" is intended to include various forms
25 of said element, for instance both curved and
straight forms.

The invention has, for its particular ob-
ject, to provide a work support which will
have capacity for ready adjustment of the
30 horn to meet the varying requirements of
different work upon which the machine may,
at different times, be required to operate, and
which will enable the operator readily to de-
termine the position of adjustment of the
35 horn required by any piece of work and yet
be generally convenient to manufacture and
use and to maintain in condition.

An important feature of the invention re-
sides in the provision of a horn freely rotat-
40 able about a supporting member mounted
for up and down movement to effect adjust-
ment of the horn and devices for latching
the horn to the supporting member to enable
the supporting member and consequently the
45 horn to be adjusted by manipulation of the
horn.

Another important feature of the inven-
tion resides in the provision in a work sup-
port of the type comprising a work support-
50 ing post projected from the machine frame
by yielding means and arranged to be de-
pressed in each cycle of operations of the ma-
chine against the yielding means, of novel
connections between the post and the de-

pressing mechanism constructed to permit 55
relative adjustment of the post and the de-
pressing mechanism and means for varying
the amount of normal projection of the post
from the machine frame upon such adjust-
ment. The work supporting post is prefer- 60
ably projected from the machine frame by a
spring, and in accordance with a still fur-
ther feature of the invention the character
of the connections between the post and the
depressing mechanism and the construction 65
of the means for varying the amount of nor-
mal projection of the post from the machine
frame are such that by a single adjustment
the amount of normal projection of the post
from the machine frame may be varied with- 70
out changing the tension of the spring.

Other objects and features of the invention
will become apparent as the description pro-
ceeds and will be pointed out in the ap-
75 pended claims.

In the drawings,

Fig. 1 is a view in side elevation of a fas-
tening inserting machine having the inven-
tion applied thereto;

Fig. 2 is a view in side elevation of the 80
work support showing the means for adjust-
ing the horn post in cross section;

Fig. 3 is a plan view of the adjusting mech-
anism for the horn post taken along the line 85
3—3 of Fig. 2 and looking in the direction of
the arrow, and

Fig. 4 illustrates the devices for securing
the horn to the horn post.

The illustrated machine is a well-known
form of fastening inserting machine design- 90
ed for the insertion of loose nails. It com-
prises a column 2 upon which is mounted a
head 4 carrying a hopper 6 which constitutes
a source of supply of nails to the nail insert-
ing instrumentalities of the machine. The 95
hopper 6 and the nail inserting instrumen-
talities are operated from a shaft 8 journaled
in the head 4 and controlled through suit-
able clutch mechanism by a treadle 9.

The work is presented to the machine 100
against the under surface of a presser plate
10 and is upheld against the plate 10 by a
work-engaging and supporting element 11
which, as shown, has the form of a curved
horn. The horn 11 is carried by a member 105
12 mounted to rotate freely on a horn post
13 sleeved into an extension 14 rising from
the column 2 of the machine. As shown, the

member 12 is supported on the horn post 13 by a shoulder 15 on the horn post. The upturned lower end of the horn 11 is received in a split bearing in the member 12 and is positioned vertically in the bearing by a shoulder 115 on the horn. The horn may be clamped in its bearing by a screw 16. When the screw 16 is slackened, the horn may be turned so as laterally to adjust its tip with relation to the horn post 13, and the horn may then be secured rigidly in position in its bearing by again tightening the screw 16. The horn post 13 is connected at its lower end to a carrying member or spindle 17 operatively mounted in the machine frame and having coiled about it a spring 18 tending to move the spindle 17 upwardly and thereby to press the work against the plate 10. In order to facilitate the movement of the work over the horn 11, the spindle 17 and, consequently, the horn post 13 is depressed in each cycle of operations of the machine. To this end, a rod 20 at the rear of the machine is connected to the spindle 17 by a lever 22 fulcrumed at 24 on the machine frame and is raised to depress the spindle 17 by a second rod 26 to which movement is imparted from the main shaft 8 and which is provided with a pawl 28 adapted to engage ratchet teeth formed on the rod 20. The portion of the frame of the machine adjacent to the lower end of the horn post 13 serves as an abutment against which a collar 30 on the horn post acts to limit the amount of normal projection of the horn post by the spring 18. A washer 32 may be, and as shown is, interposed between the collar 30 and the machine frame.

The construction and arrangement of the pawl 28 and the teeth on the rod 20 are such as to cause the horn 11 to lower the work from the presser plate 10 by equal amounts regardless of variations in the thickness of the work. It is found, however, in the use of work supports of the character hereinbefore described that when the thickness of the work differs very greatly the work support does not operate efficiently, one reason for this being that the degree of tension of the spring 18 varies in direct ratio with the thickness of the work. For instance, when work of relatively great thickness is placed on the horn 11, the tension of the spring 18 is correspondingly increased. Accordingly, it is necessary in order to enable the work support to operate efficiently for the horn 11 to be adjusted with relation to the spindle 17. To this end, in the present instance of the invention, the horn post 13 is hollowed out at its lower end and is threaded on the spindle 17 so that when the post is rotated it will be adjusted relatively to the spindle. It is desirable also that the amount of normal projection of the horn post 13 from the machine frame shall be varied in accordance

with the relative adjustments of the horn post and the spindle 17. For illustration, if the horn post 13 is screwed down on the spindle 17 to adjust it to work of greater thickness than that previously operated upon, it is desirable that the amount of projection of the post from the machine frame as determined by the collar 30 shall be decreased, thus lessening the extent to which it is necessary for the operator to lower the post in placing work on and removing it from the horn 11. In order to enable the amount of normal projection of the horn post 13 from the frame to be changed when the horn post is adjusted on the spindle 17, the collar 30 is threaded on the horn post and is maintained against rotation with the horn post by means hereinafter to be described. The threads connecting the collar 30 to the horn post 13 are made of a lead substantially equal to the lead of the threads connecting the horn post to the spindle 17, so that rotation of the horn and the resultant adjustment of the horn post on the spindle 17 does not affect in any way, the relation between the collar 30 and the spindle 17. Consequently, the tension of the spring 18 will be the same in all positions of normal adjustment of the horn post 13. One of the advantages of this construction is that it establishes uniform conditions of operation of the machine inasmuch as the resistance opposed by the spring 18 to the lowering of the horn post from normal position to facilitate the placement of work on or removal of work from the horn 11 will remain constant regardless of adjustments of the horn post. In order to enable the horn post 13 to be secured rigidly in adjusted position, the hollowed lower end of the post is slotted, as shown at 34, and the collar 30 is split, as indicated at 36 (see Fig. 3). A screw 38 seated in a ring 40 embracing the collar 30 serves to clamp the collar 30 and the slotted part of the horn post 13 on the spindle 17. As shown, the screw 38 is formed with a reduced end adapted to be received in a slot 42 in the collar 30. A stud 44 threaded into the frame 2 of the machine is received in an elongated slot 46 disposed vertically in the ring 40, and the ring 40 is provided with a pin 48 extending into an opening in the collar 30. With this construction, rotation of the collar 30 with the horn post 13 is prevented, whereas the collar is at the same time allowed to move freely with the horn post when it is depressed by the spindle 17.

In so far as the operation of the horn post controlling and adjusting means is concerned, the rotation of the post may be effected in various ways. In the present instance of the invention, however, the member 12, which carries the horn 11 is provided with devices for securing said member to the

horn post 13 so that rotation of the horn post 13 and consequent adjustment of the horn 11 may be effected through manipulation of the horn. As shown, such securing devices comprise a latch pin 50 urged inwardly by a spring 52 to engage the nose of the pin in a notch 51 formed in the horn post. The latch pin 50 is provided with a stud 54 received in a slot or notch 56 in the member 12, the construction being such that when the stud 54 is engaged in the notch 56, the latch pin 50 will be moved into latching engagement with the horn post whereas when the stud 54 is withdrawn from the notch 56 and engaged with the outer surface of the member 12, the latch pin 50 is maintained out of latching engagement with the horn post.

A scale 58 is fixed by screws 60 adjacent to an opening formed in the sleeved extension 14 of the column 2 and an index mark 62 is provided on the horn post 13. By this means the thickness of the work being operated upon may be readily ascertained and the suitable length of fastening to be used in accordance therewith determined.

When work is being operated upon by the machine, the latch pin will be disengaged from the notch 51 in the horn post 13, and the horn 11 will then be free to rotate about the horn post. During the operation of the machine also the screw 38 will be tightened to clamp the collar 30, the horn post 13, and the spindle 17 together so as to prevent relative rotation of such parts when the horn 11 is rotated on the horn post 13. When it is desired to adjust the height of the horn 11, however, the screw 38 will be slackened, and the latch pin 50 will be engaged in the notch 51 of the horn post. The operator may then use the horn 11 as a hand lever to rotate the horn post 13 and to raise or lower it as desired through the collar 30. The amount of vertical adjustment of the horn 11 will be readily seen on the scale 58.

When it is desired to measure the thickness of the work to be operated upon and to determine thereby the correct length of nails to be used, the horn 11 will be adjusted vertically until the index mark 62 is opposite the minimum on the scale 58. The horn will then be lowered by the usual horn lowering treadle 64 and the work placed on the horn. When the horn is raised, the thickness of the work clamped by the horn against the presser plate 10 will be readily seen.

Having thus described my invention, what I claim as new and desire to secure by Letters Patent of the United States is:

1. In a machine of the class described, the combination of a supporting member, a horn normally freely rotatable on the supporting member, means for mounting the supporting member for up and down move-

ment to adjust the horn, and a latch for securing the horn to the supporting member to enable the supporting member and horn to be adjusted by manipulation of the horn.

2. In a machine of the class described, the combination of a horn, a member for supporting the horn, connections between the horn and the supporting member constructed to permit the horn to rotate freely on said member during operation of the machine, controlling means for the supporting member operable to adjust the horn upon rotation of the supporting member, and means for securing the horn to the supporting member so that adjustment of the horn may be effected by rotation of the supporting member through manipulation of the horn.

3. In a machine of the class described, the combination of a horn, a horn post, connections between the horn and the horn post constructed to permit the horn to rotate freely on the horn post during operation of the machine, mechanism for raising and lowering the horn post, connections between the horn post and said mechanism constructed to adjust the horn upon rotation of the horn post, and a latch for securing the horn to the horn post so that adjustment of the horn may be effected by rotation of the horn post through manipulation of the horn.

4. In a machine of the class described, a horn post, a horn normally loosely mounted on the horn post, a member for supporting the horn post, connections between the horn post and said member constructed to adjust the horn relatively to said member upon rotation of the horn post, and a spring latch for securing the horn to the horn post so that adjustment of the horn post and the horn relatively to said member may be effected by manipulation of the horn.

5. In a machine of the class described, the combination of a frame, a work supporting post slidably mounted on the frame, yielding means for projecting the post from the frame, means for depressing the post in each cycle of operations of the machine against the yielding means, connections between the work supporting post and the depressing mechanism constructed to permit relative adjustment of the post and said mechanism, and means operating to vary the amount of normal projection of the post from the machine frame as the post is adjusted relatively to the depressing mechanism.

6. In a machine of the class described, a frame, a work supporting post slidably mounted on the frame, yielding means tending to move the post with relation to the frame, a member on the post for limiting its movement by the yielding means, mechanism for depressing the post in each cycle of operations of the machine against the yielding means, and connections between

the post and the limiting member and the depressing mechanism respectively constructed and arranged to enable the position of the limiting member on the post and, 5 consequently, the amount of projection of the post from the frame to be varied by a single adjustment and to maintain the relation of the limiting member to the depressing mechanism substantially unchanged by such 10 adjustment.

7. In a machine of the class described, a frame, a horn post slidably mounted on the frame, a horn on the horn post, yielding means tending to move the horn post with 15 relation to said frame, a member threaded on the horn post for limiting the movement of the horn post by the yielding means, means for constraining the limiting member against rotation so that the position of 20 the member on the horn post and, consequently, the amount of projection of the horn post from the frame may be varied by rotating the horn post, mechanism for depressing the horn post in each cycle of operations 25 of the machine against the yielding means, and connections between the horn post and the depressing mechanism constructed to maintain the relation of the limiting member and the depressing mechanism substantially 30 unchanged by the rotation of the horn post.

8. In a machine of the class described, a frame, a work supporting post slidably mounted on the frame, a member for supporting the post, yielding means tending to 35 move the post with relation to the frame, means for limiting the movement of the post by the yielding means, connections between the limiting means and the post constructed to cause rotation of the post to effect relative movement of the post and the limiting means and thus to vary the amount of projection of the post from the frame, and connections between the post and the supporting member constructed to maintain the relation 40 of the limiting means and the supporting member substantially unchanged by the rotation of the post.

9. In a machine of the class described, a frame, a horn post slidably mounted on the 45 frame, a horn on the horn post, mechanism for depressing the horn post in each cycle of operations of the machine, comprising a spindle, yielding means operating on the spindle and tending to move the horn post with relation to the frame, means for limiting the movement of the horn post by the yielding means, connections between the limiting means and the horn post constructed to cause rotation of the horn post to effect 50 relative movement of the horn post and the limiting means and thus to vary the amount of projection of the horn post from the frame, and connections between the horn post and the spindle constructed to maintain 55 the relation of the limiting means and the

spindle substantially unchanged by the rotation of the horn post.

10. In a machine of the class described, the combination of a spindle, a horn post threaded on the spindle, a horn on the horn post, an abutment to which the horn post is relatively movable, yielding means operating on the spindle and tending to move the horn post with relation to the abutment, a member for limiting the movement 75 of the horn post said member being threaded on the horn post and restrained against rotation so that rotation of the horn post will effect adjustment of the horn post and horn with respect to the abutment, and a scale 80 fixed relatively to the abutment for indicating the position of the horn post with respect to the abutment.

11. In a machine of the class described, the combination of a spindle, a work supporting post threaded on the spindle, an abutment with respect to which the post is relatively movable, yielding means operating on the spindle and tending to move the post with relation to the abutment, and a 90 collar on the post for limiting the movement of the post, the collar being connected to the post by threads having a lead substantially equal to the lead of the threads connecting the post with the spindle so that the post may be adjusted relatively to the spindle and said abutment by rotation of the post without changing the relation of the collar and the spindle.

12. In a machine of the class described, the combination of a frame, a work supporting post slidably mounted on the frame, means for yieldingly projecting the post from the frame comprising a spindle threaded into the lower end of the post, a collar 100 threaded on the exterior of the post for limiting the amount of normal projection of the post from the frame, and means for maintaining the collar against angular movement so that the position of the collar on the post and consequently the amount of projection on the post from the frame will be varied upon rotation of the post to effect relative adjustment of the post and the spindle.

13. In a machine of the class described, the combination of a spindle, a horn post threaded interiorly on the spindle, a horn on the horn post, an abutment to which the horn post is relatively movable, yielding means operating on the spindle and tending to move the horn post with relation to the abutment, mechanism operating on the spindle to depress the horn post during each cycle of operations of the machine, a collar 110 threaded exteriorly on the horn post for limiting the movement of the horn post, and connections between the collar and the abutment constructed to permit movement of the 115 collar with the horn post when the horn post 120

is depressed but to prevent angular movement of the collar.

14. In a machine of the class described, the combination of a frame, a horn post 5 slidably mounted in the frame, a horn on the horn post, yielding means tending to move the horn post with relation to the frame, a split collar threaded exteriorly on the horn post for adjustably limiting the movement 10 of the horn post by the yielding means, means for restraining the collar against angular movement with the horn post, and means for clamping the collar on the horn post to maintain the horn post against rotation with relation to the collar thereby to 15 secure the horn post in adjusted position.

15. In a machine of the class described, a frame, a spindle carried by the frame, a horn post sleeved into the frame and having 20 its lower end slotted and interiorly threaded to engage the upper end of the spindle, a horn on the horn post, a split collar mounted exteriorly on the horn post and connected to the horn post by threads having 25 a pitch substantially equal to the pitch of the threads securing the horn post to the spindle whereby rotation of the horn post may be effected without changing the relation of the collar to the spindle, means operable on the spindle to project the horn post from the frame to an extent determined by the engagement of the collar with the frame, controlling means for the collar comprising means for clamping the collar on 30 the horn post to prevent rotation of the horn post in the collar, and connections between the controlling means and the frame constructed to permit bodily movement of the collar with the horn post but to prevent 35 angular movement of the collar.

16. In a machine of the class described, the combination of a frame, a spindle operatively mounted in the frame, a horn post sleeved into the frame and having its lower 40 end slotted and interiorly threaded for engagement with the spindle, a horn on the horn post, a split collar threaded exteriorly on the horn post, a ring embracing said collar, means carried by the ring for clamping 45 the collar on to the horn post to prevent relative movement of the horn post and

the collar, connections between the ring and the collar for preventing relative rotation of the ring and the collar, and connections between the ring and the frame for preventing rotation of the clamp and, consequently, of the collar. 55

17. In a machine of the class described, the combination of a frame, a work supporting post mounted on the frame, means 60 for yieldingly projecting the post from the frame, connections between the post and said means constructed to permit relative adjustment of said parts, and means arranged progressively to vary the amount of 65 normal projection of the work supporting post from the frame as the post and said projecting means are relatively adjusted.

18. In a machine of the class described, the combination of a horn post, a horn normally freely rotatable on the post, and a latch for securing the horn rigidly to the post. 70

19. In a machine of the class described, the combination of a horn post, a carrying member screw-connected thereto, a collar screw-connected to the horn post and arranged for engagement with a stationary portion of the machine to limit movement in one direction of the horn post, the leads 75 of the screws of the two connections being equal so that adjustment of the post with respect to the carrying member will not change the relation of the carrying member to the collar. 80

20. In a machine of the class described, the combination of a horn post, a carrying member therefor, and a restraining member connected thereto and arranged to limit movement of the horn post in one direction, 90 the horn post and the restraining member being screw connected for relative longitudinal adjustment and the connection of the restraining member to the carrying member being such that rotation of the horn post to cause its adjustment with respect to the restraining member will not change the relation of the restraining member to the carrying member. 95

In testimony whereof I have signed my name to this specification.

WILLIAM THOMAS BUCKINGHAM ROBERTS.
